DENTAL FLASK

Nathan Opotow, New York, N. Y.

Application November 13, 1946, Serial No. 709,566

6 Claims. (Cl. 18—33)

1

This invention relates to dental flasks used by dentists and dental technicians for forming partial or full artificial dentures.

The present application is a continuation in part of my application Serial No. 634,735, filed December 13, 1945, now Patent No. 2,440,910.

As recited in the above mentioned patent application, artificial dentures are usually made by investing an upper or lower model of the jaw structure into the lower portion or section of a dental flask together with the waxed-up case representing a prototype of the finished denture. The surface of the plaster which invests the model is then coated with oil or soap and the upper section of the flask is thereafter applied over the lower section and filled with plaster or artificial stone or any other suitable component serving as investing material. The cover is then applied and the material is allowed to set. Thereafter, the assembled flask is immersed in boiling water for several minutes, whereupon the upper section of the flask is separated from the lower section. The wax of the waxed-up case is now washed or flushed out, it having been melted or softened during the boiling process. A thermoplastic material, such as various acrylates, or any other suitable denture material, is then applied to the space left by the wax, and the upper portion of the flask is restored. The reassembled flask is then subjected to pressure in order to distribute the plastic material properly. The flask is ordinarily re-opened thereafter and more material is added until, when pressure is reapplied, the surplus material within the flask is forced through the line where the flask halves meet. The flask is again opened and all excess material from the investment portion is removed, but not from the denture. Then the flask is subjected to considerable pressure to force out any excess of material over the denture until the flask is properly closed so as to maintain the original plan of the denture. The flask is now processed by heat to cure the denture material. It is a well known fact that upon curing, the volume of the denture material decreases considerably. Consequently, the accuracy of the finished denture suffers. In fact, some techniques utilize an over-supply of material which maintains the flask slightly open even when under pressure. In such techniques, the surplus material is expected to compensate for curing shrinkage. However, it is practically impossible to both gauge the amount of curing shrinkage actually so as to predetermine the degree of over-supply and to determine where, in the various regions

2

of the denture, the surplus should be applied. Furthermore, it is to be observed that a function of the excess is to apply pressure to the material whereas, if the excess becomes substituted for the shrunken material, a proportional pressure loss is encountered. A solution often practiced is to apply a great excess of material, but this merely opens the flask more and decreases the accuracy of the finished denture. In addition, a method known as injection molding is often practiced but whereas it is possible to continue the supply of material as necessary under this method, it is extremely difficult to achieve a proper distribution of the added material.

15 Thus, the above known methods, while generally practiced throughout the industry, involve many difficulties and are productive of unsatisfactory results in a large percentage of cases. In general, the principal objection is the production of discrepancies between the wax pattern and the cured denture through alteration of the planned occlusion.

It is further noted that a method, sometimes referred to as a "banking" procedure, has been 25 practiced but only for small, partial dentures. This method avoids the necessity of separating the teeth and model after the wax has been washed away. It is accomplished by investing the teeth and model in one half of the flask, while 30 baking the plaster around the teeth and model far above the height of the flask portion in which it is invested. The upper portion is formed with a mound of plaster in the form of a plunger, the wax is eliminated as previously, and the denture 35 material is applied through the lingual side of the case. This method permits a sufficient or even a highly excess supply of plastic denture material to compensate for the curing shrinkage and to assure proper compression.

40 Processing of the artificial denture by the banking method above described has not been generally adopted in spite of its benefits because of other difficulties which have made its use impractical in many cases. Thus, the banking procedure may be employed where small partial dentures are required, but it is rarely or never employed where an extensive partial or a full denture is to be prepared. The principal difficulty has been the fact that the application of pressure 45 to force the plastic material into place and to insure proper compression thereof, very often cracks the banked wall of plaster and virtually destroys the denture. In my application described above, I disclosed a substantially three-piece dental flask wherein a banking process

can be employed while virtually eliminating the danger of fracturing the built-up plaster or the model. The flask permitted free access, both physical and visual, to the invested teeth so that the plastic denture material could be applied with 5 ease and precision.

The instant invention accomplishes the objects set forth in said prior application in overcoming most or all of the defects of prior devices, but is 10 of further advantage in insuring the accuracy of the finished denture. This objective is realized by converting the flask of the prior patent application from a three-piece to a two-piece construction so as to eliminate as far as possible 15 undesired displacement between the flask sections and insure accuracy throughout the procedure, although high pressure may be used as required.

Other objects of my invention will be apparent from the following description, it being understood that the above general statements of the objects 20 of my invention are intended to describe and not limit it in any manner.

Referring to the drawing:

Fig. 1 is a perspective view of the top flask 25 section.

Fig. 2 is a perspective view of the lower flask section.

Fig. 3 is a rear elevational view of this flask, shown partly broken away to illustrate the floor knockout block thereof.

The flask comprises the lower section or receptacle 10 having a conventional knockout block 10a to facilitate removal of the finished denture. Receptacle 10 is formed with a surrounding wall 11. Lugs or pins 12 formed on the upper surface 15 of receptacle 10 complement the openings 13 and 14 of flask upper section 15.

Section 15 is formed with a ceiling 16 and a depending wall 17 which though considerably smaller than wall 11, is nevertheless of such a size as to embrace a mound of plaster as will be hereinafter described. Upper section 16 is formed with an off-set member in the form of depending flange 18 which fits into an appropriate cutout 19 of receptacle 10. Thus, referring to Fig. 3, when the upper and lower flask sections are assembled, the flask assumes its closed position whereby pressure may be applied to the contents as above described.

In order to utilize the improved dental flask, the teeth in the form of a waxed-up case and the model of the jaw structure are invested in the receptacle 10. The investment while in the receptacle is then coated with oil, soap or any other separating material, and more plaster is applied thereover. Then the upper section 15 is applied in position. After setting, the plaster last applied is retained by the upper section 15, the openings 20 and 21 of which function as gripping means for the set plaster. When the section 15 with the set plaster thereon is withdrawn, the plaster is in the shape of a mound which functions as a plunger for compressing the artificial denture material thereafter applied. Indentations 22 and 23 in the upper section 15 are provided to facilitate separation of the flask sections by an appropriate tool.

When the upper section 15 and the plaster-filled flask enclosing the model and waxed-up case are assembled, and the plaster has set, the flask is heated so as to boil out the wax which held the artificial teeth. These teeth will now be retained in the plaster of the receptacle 10 so that the flask may be separated without altering their position.

The wax having been boiled away, the teeth will

be separated from the model gum ridge which will likewise be retained in its original position. Cutout or opening 19 then serves the function of a window through the upper, rear area of wall 11 by which the teeth can be seen and cleaned of foreign material. Furthermore, the denture material may be applied through the cutout 19 since the teeth and model gum ridge are fully accessible both visually and physically from a rear lateral portion of the lower flask section. It will be noted that front wall portion 11a surrounds and protects the set plaster material adjacent the teeth so as to protect the case against fracture when the upper member 15 is thereafter applied with pressure. Inasmuch as the teeth and model can have no relative movement after the investment, a sufficient quantity of dental material to compensate for curing shrinkage can be applied without risking any change in the cured denture.

The upper section, having the set plaster mound thereon held by the openings 20 and 21 and by the depending wall 11, is restored to the complementary lower section. The wall 17, which surrounds the upper section and nests in the cutout 19, may be about $\frac{1}{2}$ inch in height to embrace a portion of the mound. The assemblage is then subjected to pressure in a bench press whereupon the mound compresses the plastic denture material so that it fills the space left by the boiled out wax. The degree of compression can be very great, if desired, without fracturing the plaster investment since the wall section 11a provides a firm backing for the teeth and plaster behind it. The application of a considerable over-supply of denture material is made possible to assure sufficient compression and density without altering the planned occlusion.

After initial pressure, the flask may be reopened for the application of further denture material to insure against a possible deficiency. Such re-opening, of course, cannot affect the occlusion because the teeth remain fixed in the lower section. A compensating spring press is thereafter applied to the assembled flask which is then boiled for a conventional period of time, approximately one hour, depending upon the material used. The spring press is then taken off and the finished denture is removed in the usual manner. It has been found that with the three-piece construction of my former application, the intermediate piece would sometimes separate slightly from the lower section due both to the resiliency of the plastic material in the bench press and to its tendency to expand when curing in the spring press. Such a separation, in some instances, might crack the plaster although, in the majority of instances, this did not occur. In the present construction, however, this is avoided because of the unitary or integral nature of the lower section.

It will be apparent that the improved dental flask can also be utilized for investment procedures wherein the artificial teeth are retained in the removed section, if this procedure is desired.

It may be noted that, in the instant application, the depending flange 18 is a portion of the upper section 15 so as to back up the mound formed on the section 15 and enhance its retention thereon. The wall 17 cooperates with the flange 18 in this respect. Section 15, although being a distinct flask section, is also a cover or closure member for the flask in distinction to the usual, substantially flat plate used for this purpose.

I have shown a preferred embodiment of my invention, but it is obvious that numerous

changes and omissions may be made therefrom without departing from its spirit.

I claim:

1. A dental flask comprising a pair of complementary upper and lower sections, said lower section having a surrounding wall and an opening formed in a rear portion thereof adapted to permit lateral access to the interior of said lower section, and an offset member integral with said upper section for covering said opening when said upper and lower sections are assembled, and plaster retaining means on said upper section so as to retain a mound of set plaster by embracing a portion thereof, said upper section serving as a cover for the flask.

2. A dental flask comprising a pair of complementary upper and lower sections, said lower section having a surrounding wall and having an area thereof cut away to define an opening so as to permit lateral access to the interior of the lower section, and a depending member on said upper section formed so as to nest in said area and to substantially close said opening when the flask is assembled, said upper section being of a depth to maintain a mound of set plaster therein whereby said mound may be forced into said lower section when the flask is assembled and pressure is applied thereagainst, said upper section serving as a cover for the flask.

3. A dental flask comprising a pair of complementary upper and lower sections, said lower section having an integral surrounding wall, a rear portion of said wall being cut away at its upper half so as to permit lateral access to the interior of said lower section from the rear side of said flask, said upper section being adapted to be assembled with said lower section so as to form a substantially complete flask, and a depending flange on said upper section having the same dimensions as said cut away portion so as to nest

therein and close the opening formed by said cut away portion.

4. A dental flask comprising a lower model investing section and closure means therefor, a surrounding wall integral with said lower section, an upper rear area of said wall being cut away substantially from side to side of the flask so as to form an opening and permit lateral access to the interior of said lower section, and a flange on said closure means for covering said opening when the flask is assembled.

5. A dental flask according to claim 4 wherein said closure means comprises an upper section formed with a surrounding wall of a depth sufficient to retain a mound of set plaster by embracing a portion thereof.

6. A dental flask for use in banking procedures comprising a lower model investing section, a covering section therefor, a surrounding wall integral with said lower section, a substantial portion of the rear area of said wall being cut away so as to form an opening and permit lateral access to the interior of said lower section, means on said covering section to enclose said opening when said flask is assembled, and means on said cover section to retain a set mound of plaster whereby said set mound may serve as a plunger in said banking procedure.
